(57) **CLAIM**

The ornamental design for a mini shaver, as shown and described.

DESCRIPTION

FIG. 1 is a perspective view of a mini shaver showing my new design.

FIG. 2 is a perspective view thereof, showing the mini shaver in an open state of use.

FIG. 3 is a front view thereof;

FIG. 4 is a rear view of FIG. 1;

FIG. 5 is a left side view of FIG. 1;

FIG. 6 is a right side view of FIG. 1;

FIG. 7 is a top view of FIG. 1; and,

FIG. 8 is a bottom view of FIG. 1.

The broken lines illustrate portions of the mini shaver that form no part of the claimed design.
